SLIDING DOOR HANGER ASSEMBLY

Dwight W. Blackmer, Elkhart, Ind., assignor to Ekco Products Company, Chicago, Ill., a corporation of Delaware

Filed Apr. 3, 1959, Ser. No. 803,943

1 Claim. (Cl. 16—97)

This invention relates to a sliding door hanger assembly and more particularly to hanger assemblies of this type wherein the connection between the door and the track engaging carrier of the hanger assembly may be established through interengagement of the cooperating parts by bodily movement of the door within its doorway and relative to said carrier.

It is an object of this invention to provide an improved hanger assembly having features of construction and design which facilitate installation procedures and which also renders the assembly simple and economical as well as sturdy.

A further object resides in the use of improved means for preventing unintentional disconnection of the cooperating parts in spite of relatively severe operating conditions.

Other objects and advantages of the present invention will become apparent from the following description and the accompanying drawings wherein:

Fig. 1 is a fragmentary side elevation of a sliding door installation, with a portion of the track broken away, to illustrate a hanger assembly according to this invention, when in operative condition.

Fig. 2 is a vertical section taken along line 2—2 of Fig. 1 in the direction of the arrows.

Fig. 3 is a view similar to Fig. 2 except showing the 40 bracket in a position preparatory to disposition in operative relation to the carriage member.

Fig. 4 is a horizontal section taken downwardly along line 4—4 of Fig. 1.

Fig. 5 is a view partly in section and partly in side elevation taken along line 5—5 of Fig. 4 in the direction of the arrows.

Fig. 6 is a bottom plan view of the bracket to show details of its design and construction.

The drawings illustrate a hanger assembly as applied to an installation wherein a door 10 is supported from a track 11 secured to a door frame 10A opposite the upper edge of said door.

Each hanger assembly, in accordance with a preferred embodiment of this invention, includes a carrier body having a set of rollers 12 having engagement with said track 11 for guided movement along said track. As shown, the carrier body comprises a pair of cooperating straps 13 and 14 arranged in face to face relation along opposite end areas thereof straddled by the rollers 12 while the area between said end areas is formed along lines curved outwardly in opposite directions to define a hub portion 15 having its open ends facing in upward and downward directions. The carriage body is provided with an extension in the form of a stem 16 having

2

its upper end 17 journalled in the hub 15. The portion of the stem 16 projecting downwardly from the carriage body terminates in an enlarged circular head 18. The head 18 is bevelled outwardly and downwardly along its 5 outer edge 19.

Connection between the stem 16 of the carrier body and the door 10, as contemplated by this invention, is established by means of a door mounting bracket having a plate portion 20 and an integral arm 21 extending angularly from the upper edge of the plate portion 20. The plate portion 20 is secured to the side of the door 10 along the edge thereof facing the carriage body by suitable means such as screws 22 fitted through openings in the plate portion. The arm 21 occupies a position 10 in overlapping relation to the upper edge of the door. To provide clearance between the arm and the edge of the door opposite thereto, the arm is offset upwardly along a limited area 23. The area 23 is intersected by a slot 24 extending inwardly from the edge of the arm 21 facing away from the plate portion 20 of the bracket. The slot 24 is of such dimension as to admit the stem 16 therein. The inner limits of the slot 24 presents a circular edge which is bevelled downwardly and outwardly in a direction away from the carriage body to define 15 a seat 25 complementary to the shape of and fitting closely with the edge surface 19 of the head 18. The seat 25, and the opposite edges of the slot 24 leading to said seat 25 meet to define shoulders 26 with which the edge 19 of the head 18 has engagement to resist withdrawal of 20 the head from a position within the confines of said seat.

An annular abutment member or retainer 27 is slidably supported on the stem 16 for movement toward and away from a position against the head 18 at the lower end of the stem, and biased toward the head 18 25 under stress of a coil spring 28 encircling the stem and acting against a shoulder 29 on the stem where the latter joins the hub 15 on the carriage body.

Accordingly, as the leading edge of the arm 21 is advanced into the area between the head 18 on the stem 16 and the surface of the abutment member 27 facing said head, the abutment member is cammed upwardly against the resistance of the spring 28 a distance necessary to admit the head 18 to the area within the confines of the seat 25 at the inner limits of the slot 24. The stress of the spring 28 thereupon applies pressure against the arm of the bracket along the surface thereof facing the abutment member 27 to prevent withdrawal of said bracket from said head while the latter is within the confines of seat 25. The abutment member presents an outer circular edge 30 which is curved upwardly and outwardly in relation to the surface of the head 18 facing said abutment member 27. The bevelled edge of the head and the aforesaid edge of the abutment member thus in effect provide cooperating guides to facilitate entry 45 of the bracket arm therebetween incident to movement of the latter toward a position in which the head and the bracket are operatively assembled as a door hanger unit.

To relieve friction and to provide noiseless action between the hub 15 and the end portion 17 of the stem 16 50 engaged by said hub, a sleeve 31 of relatively friction-free synthetic resinous material is fitted around said end portion 17 of the stem 16.

What is claimed:

A sliding door hanger assembly including a track engaging carrier having a body member, a door mounting

bracket defined by a second member, one of said members having a stem secured thereto and forming an extension thereof in the direction of the other member, said latter member having a slot extending inwardly from one edge thereof in which said stem has entry in a direction radially of said stem as an axis, an enlarged head at the projecting end of said stem, said head presenting a radially facing edge portion bevelled outwardly in a direction away from the member to which the stem is secured, said slot containing member having surfaces at the inner end of said slot which are bevelled to define a seat with which the aforesaid edge portion of said head has interfitting relation when the stem is positioned within said slot, a retainer slideably carried by said stem for movement toward and away from said head and engaging 15 said slot containing member at opposite sides of the slot along bearing surfaces of said latter member facing in a direction away from said head, spring means acting

to bias said retainer toward said bearing surfaces to yieldably resist unintentional withdrawal of said head from said seat, and said retainer presenting an outer edge portion which slants outwardly in the direction of the member to which the stem is secured.
